UNITED STATES PATENT OFFICE.

LAWRENCE E. ELLIS, OF NEW YORK, N. Y.

DESIGN FOR A TEXTILE FABRIC.

• 61,089.

Specification for Design. Patented June 20, 1922.

Application filed March 9, 1922. Serial No. 1,097. Term of patent 7 years.

To all whom it may concern:

Be it known that I, LAWRENCE E. ELLIS, a citizen of the United States, residing at New York, in the county of New York and State of New York, have invented a new, original, and ornamental Design for a Textile Fabric, of which the following is a specification, reference being had to the accom-

panying drawing, forming part thereof and showing a lace design printed or embossed upon a textile fabric.

I claim:

The ornamental design for a textile fabric substantially as shown.

LAWRENCE E. ELLIS.
